UNITED STATES PATENT OFFICE

2,614,571

TANK AND SPRAY UNIT FOR CLEANSING

Alexander J. Turpin, Stewart Manor, N. Y., assignor to Hauck Manufacturing Company, Brooklyn, N. Y., a corporation of New York

Application March 19, 1946, Serial No. 655,512

2 Claims. (Cl. 134—61)

1

The invention relates to a novel apparatus for effecting the cleansing of articles such as metal castings, forgings, stampings, engines and engine parts; also to a novel tank assembly for carrying out the novel method. In the cleansing of the aforesaid items, for example, in the case of internal combustion engines, it is necessary first to cleanse thoroughly the particular object of any adhering carbon deposits, oil and other foreign matter. This has been effected, generally, by immersing the work into a tank of heated cleansing solution such as an aqueous solution of trisodium phosphate which is agitated by suitable means. Thereupon, the separated scum of oily and other matter is conveniently removed from the cleansing liquid surface through suitable gutters provided along the inner surfaces of the walls of the tank at a level somewhat above the working level, as by introducing additional volumes of the said liquid to raise the level the required degree. The work is then hoisted out of the tank and located upon a suitable rack externally thereof and is washed with water under high pressure or with hot water, which results generally in objectionably splashing the surroundings, as well as the operator.

The foregoing operations require thus, in addition to the cleansing tank, not only additional floor space and the rack for supporting a final washing of the work but also a supply of water and means to heat the same, or to increase its pressure—all of which entails considerable expense. In addition, in view of the fact that the final cleansing is effected by means of fresh water, a coating of rust forms immediately upon the surface of the work.

It is an object of the invention, in completing the cleansing operation, to eliminate entirely the use of ordinary wash water, thus avoiding rusting of the work; also, the provision of means for heating said wash water or increasing the pressure thereon.

Another object of the invention is to so effect the cleansing operation that transfer of the work beyond the cleansing tank to a new location for final cleansing thereof becomes unnecessary, thus eliminating the requirement for a supporting rack and materially reducing the handling required.

Still another object of the invention is to provide means whereby the final cleansing may be effected without the splashing of water inherent in the former systems, and to permit an operator to approach the work more closely.

A further object of the invention is to pro-

vide means for use in connection with the tank whereby the final cleansing operation may be accomplished in a manner such as to reduce the temperature effect of the cleansing medium by making use of the initial cleansing liquid, after removal of any foreign matter from its surface, for this purpose rather than utilizing water and by providing said liquid in a finely divided state for application to the work.

10 In carrying out the purposes of the invention, a novel arrangement of tank is provided in which the usual hinged lid carries at its respective ends wing elements which are adapted to fold under the lid normally, but which may be swung outwardly into the respective planes of the end walls of the tank to form a stall or spray booth and provide a semi-enclosed space with the lid when the latter is elevated. Into this space the work is to be hoisted after the soaking operation has been completed, as by well known manually or power-operated means; and while suspended therein it is sprayed with the cleansing liquid, contained within the tank, by suitable means which may be hung over the edge, for example, 15 of the front wall of the tank, practically all of the liquid returning to the tank. During the initial cleansing stage, the lid is lowered with the wings folded thereunder, and locked thereto, thus providing an air space affording additional thermal insulation for the cleansing liquid which is subjected to suitable heating and agitation by means associated with the tank.

The nature of the invention, however, will best be understood when described in connection with the accompanying drawings, in which:

Fig. 1 is a view in isometric projection of the novel tank.

Fig. 2 is a view similar to Fig. 1 but with the wing elements extended to provide with the lid a semi-enclosed space above the tank.

Fig. 3 is a longitudinal section through the tank with the lid of the tank down and its wing elements folded and secured to the underside of said lid.

Fig. 4 is a transverse section through the tank, taken on the line 4—4, Fig. 3, and looking in the direction of the arrows, the lid being elevated and the wings extended.

Referring to the drawings, 10 designates a supporting base or like support for carrying the novel tank 11 in which is to be conducted all of the cleansing operations, the said tank being generally of a conformation such that its lid 12 will be substantially rectangular. The said lid 50 is hinged along a top panel 12' at the back wall

of the tank and is provided at each end with a wing element as the panels 13 and 14, respectively. These panels are swingably attached by hinging the same at the respective side edges of the lid 12 in a manner such that they may be swung inwardly beneath the under surface of lid 12, as is indicated in Fig. 3, and to be attached thereto temporarily by respective and manually operable latching members 15 and 16. The said wing elements are to be maintained in this position during the initial cleansing operation, viz: immersion of the work in a suitable cleansing liquid 17 contained in the tank 11, the lid during this period being lowered, for example, by means of the handles 18, to close the tank and its wing portions then assisting in thermally insulating the tank contents by interposing a layer of air.

Provision is made to heat the liquid during this period, for example, by means of a burner 20 discharging into a flue system 21 located along the bottom of the tank and preferably at the rear thereof, the flue system being provided with a discharge stack 22 extending through the top panel 12' of the tank. An air type agitator indicated at 23 serves to stir the cleansing liquid. Such arrangement, together with the various cleansing liquid supply and drain connections, is well understood in the art and no claim is made thereto. Also, it is desirable to insulate thermally the tank walls in the usual manner, and it is preferred to locate a baffle plate 21' in front of the flue system 21, said baffle being displaced somewhat from the bottom of the tank to enhance circulation of the liquid in said tank in the heating thereof.

After the soaking period has been completed, it has been customary to withdraw the work from the tank by suitable hoisting means (not shown) and to deposit it externally of the tank for removal of the loosened carbon deposits, oil and other foreign matter. This is generally effected by spraying the work with hot water, the objections to which have hereinbefore been noted.

In accordance with the invention, the work is not removed from the tank apparatus after the soaking operation, but the portion to be rinsed is merely elevated somewhat above the level of the liquid 17 therein, as is indicated in Fig. 2. The wing elements 13 and 14 are then unlatched, the lid 12 having been elevated previously to accommodate the hoisting of the work above the liquid; and the said wing elements are swung outwardly to lie substantially in the respective planes of the corresponding side walls 24, 25 of the tank. They are conveniently retained in this position by slipping their lower edges behind lugs 26, 27 extending inwardly from said side walls.

A semi-enclosed space 28, Fig. 2, open only at the front and top is thus afforded by the hood in the manner described, the lid 12 forming a background and the wing elements 13 and 14 side walls about the work 29, as is indicated. The said work is thus in a convenient location for the final cleansing operation, the discharge of a cleansing medium thereon being effected from the front and directed toward the suspended work 29 with the lid serving as a background to prevent scattering of the medium beyond the confines of the said tank with the positioned wing elements assisting in a lateral direction.

The spraying operation may be effected in various ways, but it is preferred to conduct this final cleansing of the work in a manner which will not

only avoid the formation of rust subsequently upon the work surfaces, but also will serve to reduce appreciably the effective degree of temperature of the cleansing medium to which an operator may be subjected, so that it becomes possible for him to approach more closely the work, than has been the case heretofore, and thus more effectively secure its final cleansing.

To this end, the liquid utilized is atomized to a relatively fine, high velocity spray; and, furthermore, use is made of the initial cleansing liquid rather than hot water as has been the practice heretofore. The liquid, of course, will first have the scum, resulting from the immersion operation, removed as by raising the level thereof to an extent to flow off the objectionable scum through a suitable scum gutter 30 provided along a side panel 25, as is well understood. Thereupon, a spray device 31 including a weighted suction pipe 32 extending into the liquid 17 and an atomizing line 33, for example, for compressed air or steam, is operated to direct the spray against the work. The said spray device may be supported conveniently for operation by the top edge of the front wall 34 by suspending it thereover, as by means of the hook 35 of said device.

I claim:

1. The combination with a cleansing tank comprising bottom, front and rear, and side walls to afford an open container for a cleansing liquid; a lid member for the tank hinged at the rear wall, and end wing members secured to opposite ends of the lid member to fold thereunder, together with manually operable latching elements to attach the wing members to the under face of the lid member when the latter closes the tank and adapted for release of the wing members when the lid is in elevated position, said wing members being adapted then to be extended outwardly therefrom substantially into the respective planes of the side walls to provide with the lid member a spray shield; of a spray unit, having means for removably supporting the same over the upper edge of the front wall of the tank, whereby to cleanse an article elevated out of the interior of said tank and suspended in the space above the same and within the partial enclosure defined by said shield, which latter confines substantially within the said space spray from the spray unit directed to said elevated article.

2. The combination claimed in claim 1, wherein the spray unit includes a suction pipe adapted to extend into the tank when said spray unit is supported over the upper edge of the front wall of the tank.

ALEXANDER J. TURPIN.
